UNITED STATES PATENT OFFICE.

JAMES H. BOYE, OF CHICAGO, ILLINOIS, ASSIGNOR TO THE BOYE NEEDLE CO., OF CHICAGO, ILLINOIS, A CORPORATION.

BED ATTACHMENT.

1,107,749.

Specification of Letters Patent. Patented Aug. 18, 1914.

Application filed November 15, 1912. Serial No. 731,504.

To all whom it may concern:

Be it known that I, JAMES H. BOYE, a citizen of the United States, and a resident of the city of Chicago, county of Cook, and State of Illinois, have invented certain new and useful Improvements in Bed Attachments, of which the following is a specification.

My invention relates to improvements in supports for drapery and the like and more specifically to improvements in supports for pillow shams and draperies for beds.

The object of my invention is the production of a support of the character mentioned which will be of durable and economical construction, which may be readily and expeditiously attached or detached, and which will be of high efficiency in use.

Other objects will appear hereinafter.

The invention consists in the combinations and arrangements of parts hereinafter described and claimed.

The invention will be best understood by reference to the accompanying drawings forming a part of this specification, and in which—

Figure 1 is a perspective view of a bed to which are applied pillow sham and drapery supports embodying my invention, portions of the pillow shams being broken away in order to expose underlying parts, Fig. 2 is a perspective view of one of the fastening members adapted for coöperation with the ends of the resilient supporting member of the device, detached, Fig. 3 is a fragmentary perspective view of an end portion of the resilient supporting member which is adapted for engagement with the fastening member shown in Fig. 2, Fig. 4 is a view similar to Fig. 3 showing the fastening member which is designed for coöperation with but a single resilient supporting element, that shown in Fig. 2 being adapted for coöperation with two supporting members, Fig. 5 is a vertical transverse section illustrating the releasable clamping of the over-lapping ends of the embracing bands of the fastening members, and Fig. 6 is a fragmentary sectional view illustrating the mounting of the pillow sham or drapery upon the resilient supporting element of the device.

The preferred form of construction as illustrated in the drawing comprises a fastening member consisting of a band or body

1 of resilient or spring metal. The band 1 is split, the over-lapping ends thereof being releasably and adjustably clamped together by means of a screw or headed member 2 which passes through said over-lapping ends, a nut 3 threaded upon said screw coöperating with the head thereof in the clamping operation, as will be readily understood. One of said over-lapping ends is bifurcated or slotted as at 4 in order to permit of sliding of said over-lapping ends to disengagement without necessitating the detachment or removal of the screw 2, this construction being adopted in order to facilitate attachment of the device to the bed post or other construction in conjunction with which the device is used. Ears 5 are formed upon one of the over-lapping ends of the band 1 which loosely embrace the bifurcated end of said band thereby serving as guides 75 for said end in order to maintain or hold said over-lapping ends in registration.

In using the device in conjunction with a bed, two members 1 are employed, one being fastened to each of the end posts of the head 80 of the bed, as clearly illustrated in Fig. 1. Extending between the bands 1 arranged upon said bed posts is an elongated helical spring 6 the ends of which are fastened in end members 7 which are provided at their 85 outer ends with heads 8. The heads 8 are adapted for engagement with slots 9 provided in convex loops 10 formed in the bands 1. Slots 9 are so formed that the heads 8 may be engaged therewith or moved 90 therethrough only when moved sidewise, said heads being of a conformation corresponding with said slots and of a size adapted to snugly fit the same. With this arrangement it will be seen that the members 7 and 95 hence the respective ends of the spring 6 will be securely locked to the bands 1, release of said members 7 from said slots being permitted only when said heads are moved laterally to disengagement. The spring 6 is of 100 such a length that, when the end members are in engagement with the head 8, said spring will be stretched or in tension and so that the resiliency thereof will serve to maintain the engagement of said end members with the bands 1. The pillow shams 11 are suspended from the spring 6 through the medium of pins 12 which are provided adjacent the upper edges of said shams, hooks 13 provided at the upper ends of said pins 110

being adapted to releasably engage over said spring as clearly shown in Fig. 6.

In order to adapt the device for employment as a support for drapery at the lower edge of the bed, bands 1' are employed which are identical in construction with the bands 1, except that the former are provided with two loops 10 instead of one as in the latter case. By this arrangement it will be seen that the bands 1' will be adapted to accommodate two ends or the adjacent ends of the springs 6 provided at adjacent sides of the bed as clearly shown in Fig. 1. The slots 9 will be so arranged that in use the same will open outwardly, relative to the bed so as to facilitate release of the spring ends therefrom. The loops 10 of the bands 1' are arranged in close proximity with each other as shown, so that in use the drapery 14 which is supported by the spring 6 coöperating with said members 1' will be positioned inwardly of the bed posts in order to expose the latter.

A supporting device of the construction set forth is durable and economical, the same may be readily and easily attached or detached. The shams or drapery are supported thereby in such a manner as to be adapted for ready detachment for washing and the device is of neat and finished appearance.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. In a support of the class described, the combination with two spaced posts, of an elongated resilient element extending between said posts; a band embracing each of said posts, each of said bands being split, the

ends of each of said bands being overlapped; a screw passing through said overlapping ends; a nut threaded on said screw for releasably clamping said ends together, one of said ends of each of said bands being bifurcated; a convex loop formed in each of said bands, each of said loops having a laterally opening slot larger at its rearward end than at its forward end; attaching members at the ends of said resilient member having outwardly extending tongues; and heads at the outer ends of said tongues adapted to pass snugly through said slots sidewise, said heads being of a form such that the same cannot pass through said slots when said members are turned to different positions, substantially as described.

2. In a support of the class described, the combination with two spaced posts, of an elongated resilient element extending between said posts; a band embracing each of said posts, each of said bands being split, the ends of each of said bands being overlapped; a screw passing through said overlapping ends and a nut threaded on said screw for releasably clamping said ends together, one of said ends of each of said bands being bifurcated, the other of said ends having ears embracing the longitudinal edges of said bifurcated end; a convex loop formed in each of said bands, each of said loops having a laterally opening slot larger at its rearward end than at its forward end; attaching members at the ends of said resilient member having outwardly extending tongues; and heads at the outer ends of said tongues adapted to pass snugly through said slots sidewise, said heads being of a form such that the same cannot pass through said slots when said members are turned to different positions, substantially as described.

In testimony whereof I have signed my name to this specification in the presence of two subscribing witnesses.

JAMES H. BOYE.
